COMBINATION BOWL AND RIM BRUSH

Frank J. Kapinos, New Haven, Conn., assignor to
the firm of Moran Brothers, New Haven, Conn.,
a partnership composed of George F. Moran
and Michael A. Moran

Application May 15, 1940, Serial No. 335,212

3 Claims. (Cl. 15—160)

This invention relates to brushes suitable for cleaning the interior surface of bowls and the under surface of the usual overhanging rims or recessed grooves with which bowls are provided.

The object of the invention is to provide, bound to a suitable handle, a rim brush of bristles the flare of which is determined, restored and maintained by a resilient shoulder fixedly mounted upon the handle.

Further objects are to provide, combined in one article having a common handle, the said rim brush and a bowl brush adapted to be manually plunged into a bowl for cleaning its interior surface in the ordinary manner, but with the rim brush capable upon the manual return movement to contact with the under surface of the overhanging bowl rim or groove; and to provide, bound to a suitable handle, a rim brush for use separately or in combination with a bowl brush of which alternate sections of the flared bristles of the rim brush are trimmed adjacent their binding to the handle to thereby retain only alternate tufts of bristles to best contact in turn with the under surface of the overhanging rim or groove without distorting any of the bristles of which the rim brush is comprised, the efficiency of a rim brush not only depending upon the flare which it possesses but the maintenance of that flare in its normal condition.

In the accompanying drawing the Figure 1 is an upright view of the improved brush; the Figure 2 is an upright view of the handle with an annular resilient shoulder fixedly mounted thereon; the Figure 3 is an upright view of a handle slightly modified; and the Figure 4 is a cross-section on the line 4—4 of the Figure 1.

With more particular reference to the drawing, 10 represents the brush handle with the annular resilient shoulder 11 fixedly mounted thereon, as at 11A. Also supported by the handle 10 adjacent the shoulder 11 is the combined bowl and rim brush, 12 and 12A, respectively, formed by layers of bristles bound to the handle in a manner already known to the art. No claim of invention is here made with reference as to how 45 layers of bristles are formed and bound to the handle 10 to provide the forwardly extending bowl portion of the brush, and likewise no invention is claimed with regard to an outer layer of bristles contributing both to the formation of 50 the bowl brush and the rim brush by having forwardly and rearwardly extending bristles; for it is apparently old in the art to employ multiple layers of overlapping bristles bound midway along their length around an extremity of a handle and 55

then folded, each layer upon itself, and then rebound to the handle to altogether provide forwardly extending bristles of the bowl portion of the brush, an outer layer of bristles being bound midway of their length, not folded, but with the bristles extending forwardly, completing the bowl brush, and rearwardly, forming an annular rim portion of the brush.

While the structure, as illustrated in the drawing, utilizes as its basis that which the art shows to be manifestly old yet the invention herein disclosed resides particularly in certain novel features herein introduced as an improvement in the art. In the improved structure the outer layer of bristles 12B is bound, as at 12H, to the handle 10 as were the previous layers shown to be in the earlier art, not folded however but with its bristles extending opposite ways from the binding 12H to complete in one direction the bowl brush 12 and in the other direction to provide the rim brush 12A which, in its process of construction is necessarily annular in form around the handle 10. But alternate sections of the annular formation of the rim brush 12A are then trimmed, as at 12D, substantially close to the binding 12H to leave remaining the tufts of bristles 12E and 12F, each with their terminals 12C and the open spaces 12G existing therebetween.

This invention further resides in providing the resilient shoulder 11 of any form or flexible material, but preferably of annular rubber ring structure, secured to the handle 10, as at 11A, placed snugly up against the closely trimmed terminals 12D and between the tufts of bristles 12E and 12F, the resilient shoulder 11 spreading the tufts 12E and 12F divergently, the outside diameter of the shoulder 11 determining the degree spreading apart. Not only is this resilient shoulder 11 adapted for use with the alternately trimmed sections of the annular rim brush, but it is as well adapted for use in connection with the annular rim brush itself to establish and maintain a flexible flare.

A still further improvement from the viewpoint of economy is the simple construction of the handle 10 which, as illustrated by the Figure 2, is of uniform dimension throughout its entire length.

This invention is subject, of course, to certain changes of construction of its parts without departing from the spirit or purpose thereof, and while the handle 10 is illustrated and described as having a uniform diameter throughout its entire length, the right is here reserved to em-

ploy, in connection with any of the other novel features herein disclosed, a brush handle provided with the manifestly old formations having an incline from which any layer or layers bound thereto may be made to take its slant, as illustrated by the Figure 3 where the tip 10A assumes a conical extremity.

By the foregoing description the advantages of the improved combination bowl and rim brush will be obvious; for in use when the rim portion of the brush is employed in cleaning a recessed or grooved under surface of a bowl rim, either tuft 12E or 12F may be so directed as to contact directly therewith, the tufts 12E and 12F each being in readiness with a turn of the handle 10 for a distinct alternate use as if each were a distinct brush. Before this improvement the rim brush was annular or skirt formation of such limited circumference in contrast with the larger circumference of the bowl rim that, in use where the under surface of the bowl rim is recessed or grooved, a portion of the skirt formation was of necessity cramped and distorted to the detriment of the life of the brush.

As a further advantage of the improved rim portion of the brush it will be recognized that the resilient shoulder 11 not only maintains the relatively divergent positions of the tufts 12E and 12F in normal condition but also protects against permanent bending and breaking of the bristles of the tufts 12E and 12F when in use they are jammed toward parallel alignment with the handle 10; for under such circumstances the resilient shoulder yields at the place of pressure thus relieving the strain at the fulcrum point of the bristles, the normal condition of the tufts 12E and 12F being restored as the resilient shoulder 11 is allowed to expand.

I claim:

1. A combination bowl and rim brush comprising a handle; multiple layers of overlapping bristles bound adjacent one end of the handle, the bristles extremities of said layers extending forwardly over the end of the handle to provide the bowl cleaning portion of the brush; and an outer layer of multiple relatively spaced clusters of bristles bound to the handle adjacent said end, the bristles extremities of said clusters extending rearwardly away from said end to provide spaced tufts of the rim cleaning portion of the brush.
- 5 2. A combination bowl and rim brush comprising a handle; multiple layers of overlapping bristles bound adjacent one end of the handle, the bristles extremities of said layers extending forwardly over the end of the handle to provide the bowl cleaning portion of the brush; an outer layer of multiple clusters of bristles bound to the handle adjacent said end, the bristles extremities of said clusters extending rearwardly away from said end to provide tufts of the rim cleaning portion of the brush; and a resilient shoulder member fixed to the handle under said tufts and close to the binding of said clusters.
- 10 3. A brush supported by a handle, the brush including a layer of multiple clusters of bristles secured by a suitable binding around one extremity of the handle to provide relatively spaced tufts each convergently extending away from said handle extremity; and a shoulder member secured to the handle under the tufts and close to the binding of said clusters.

FRANK J. KAPINOS.
